OXYGEN DISPENSING APPARATUS

Richard Carling, Richmond, Calif.

(20 E. 74th St., New York, N.Y.)

Filed Aug. 24, 1959, Ser. No. 835,607

3 Claims. (Cl. 137—624.11)

The invention relates to an apparatus for mixing oxygen gas with atmospheric air for controllably increasing the oxygen content of the air.

As is well known, an increase in the oxygen content of atmospheric air is desirable in certain circumstances. For example, a person needing additional oxygen to overcome fatigue or to meet general health or emergency requirements may desirably be provided with an oxygen-enriched air, even as a life-saving means. Accordingly, it is a general object of the invention to provide a particularly simple and efficient and safely usable apparatus of the character described which is particularly adapted for non-professional use at home or elsewhere.

Another object is to provide an oxygen-supplying apparatus which is arranged for its direct and ready control by a person using the enriched air.

A further object is to provide a means whereby enriching oxygen may be applied in a more-or-less confined body of air at an adjustably controlled rate depending on the requirements for a breathing use of the enriched air.

Yet another object is to provide an oxygen dispensing apparatus which is particularly adapted for its direct control and use by persons engaged in such activities as writing or reading or operating a vehicle.

An added object is to provide a manually settable oxygen-dispensing apparatus which may effect the delivery of oxygen for an adjusted predetermined and automatically limited time.

A still further object is to provide the apparatus with an oxygen-air mixer at the point of use of the reinforced air to thereby assure an even distribution of delivered oxygen in the reinforced air.

The invention possesses other objects and features of advantage, some of which, with the foregoing, will be set forth or be apparent from a consideration of the following description of a typical embodiment thereof, and in the accompanying drawings, in which,

FIGURE 1 is a diagrammatic showing of the oxygen-delivering means of the present apparatus in association with a supply flask or bottle.

FIGURE 2 is an axially upright section taken through a flow-control valve indicated in FIGURE 1.

FIGURE 3 is a view taken at the line 3—3 in FIGURE 2, and shows certain structural features of the flow valve, together with an associated electro-magnetic timing device and the control circuit thereof.

FIGURE 4 is a front elevation of the setting assembly at a control panel for the apparatus.

FIGURE 5 is an enlarged section of an air-oxygen mixing head shown in the apparatus combination of FIGURE 1.

As diagrammatically shown in FIGURE 1, the oxygen-dispensing apparatus of my invention essentially comprises a flask or bottle 1 containing compressed oxygen and mounting a usual type of discharge-pressure regulator 1' which is arranged to deliver the oxygen from the bottle through a discharge tube 2 at a constant predetermined pressure to a normally closed flow valve 3 which is arranged for its manual setting to open condition against spring resistance and for its adjusted and automatically timed electro-magnetic release by a timer 4 for its closing by spring action. A tube 5 discharges the oxygen released from the valve 3 to and through a discharge head 6 which mixes the received oxygen with the atmospheric air in any more-or-less confined space in which oxygen is

2

to be added for a breathing use of the oxygen-enriched air. A normally closed discharge valve 7 is provided in a branch of the connection between the bottle 1 and the regulator 1', whereby the bottle may be emptied of oxygen in case of an adjacent fire or other emergency.

By particular reference to FIGURES 2 and 3, it will be noted that the control valve 3 in the gas discharge line 2—5 from the container 1 to the mixing head 6 comprises a special structural combination in which a rotary valve plug 8 is normally operative to close a flow-passage 9 through the valve body 10. The valve plug 8 is constantly urged to its passage-closing disposal by a flat spiral torsion spring 11 disposed in a housing provided in part by a member 12 mounted on the plug stem 8' carrying a handle 8'', with the member 12 including a disc portion 12' having a peripheral axial flange portion 12'' encircling the spring 11 which has its outer end fixed to said flange. The inner spring end is anchored to a point on the outer side of an annular flange 10'' provided by a plate member 10' of the valve body 10 which is cooperative with the member 12 to complete the spring housing. The member 12 provides radial ratchet teeth 13 and 14 extending from its peripheral edge flange 12'' and cooperative with pawls 17 and 18 fixedly carried by pawl-carrying members 15 and 16 mounted on the valve body 10, said pawls being variously cooperative as detents with respect to said valve plug teeth 13 and 14.

As indicated in FIGURE 3, the pawls 17 and 18 are provided at laterally lapped ends of the members 15 and 16 which comprise levers intermediately pivoted to the valve body 10 at fixed pivot pins 15' and 16' extending intermediately through the levers and mutually parallel to each other and to the axis of the valve plug 8. The mutually opposite ends of the levers 15 and 16 respectively carry armatures 19 and 20 of temporarily magnetizable material which are disposed opposite the ends of temporarily magnetizable cores of like solenoids 21 and 22 fixedly mounted on the valve body, and are arranged for their energizing to rock the levers 15 and 16 to inoperatively dispose their pawls with respect to the teeth 13 and 14 when the solenoids are energized. Torsion springs 23 and 24 are constantly cooperative between the levers 15 and 16 and their respective pivot pins 15' and 16' to hold the armatures 19 and 20 fixedly spaced from the cores of the different solenoids 21 and 22 while the pawls are held in tooth-engaging position; FIGURE 3 shows the relations when both solenoids are deenergized, the tooth 14 then being retained between the pawls 17 and 18 by the actions of the positioning springs 23 and 24, whereby to normally prevent an appreciable turning of the valve plug for opening the passage 9.

Having the pawls 17 and 18 disposed, as shown in FIGURE 3, in spaced opposed relation in the path of possible movement of the tooth 14, a valve-opening turning of the valve plug 8 in either direction against the resistance of the valve spring 11 will be stopped by the engagement of the tooth between the pawls 17 and 18, unless the inoperative disposal of one of said pawls is effected by energizing the solenoid 21 or 22 cooperatively associated with it. As particularly indicated, a counter-clockwise rotation of the member 12 is required to engage the tooth 13 behind the pawl 18 of the member 16, and such a movement of the member 12 may only be effected after a disposal of the pawl 17 out of the path of movement of the tooth 14 by energizing the solenoid 21, whereby the permitted turning of the valve plug 8 by a manual operation of its handle 8'' may result in the engagement of the tooth 13 behind the pawl 18 of the spring-pressed pawl-carrying member 16 to then retain the valve plug in passage-opening position against the constant urge of the spring 11 to return it to its passage-closing position.

Means are preferably provided for limiting the rota-

tion of the valve plug 8 to a fixed ninety-degree angle between its passage-opening and passage-closing positions. As particularly shown, stop members 26 and 27 respectively provided on the stem-carried member 12 and on the valve body 10, are arranged for their mutual engagement when the valve is closed, with one of said members preferably being wholly or in part of resilient yielding material for absorbing the shock of stopping the valve-closing movement of the plug produced by the spring 11. When the valve plug 17 is rotated to open the flow passage 9, the tooth 14 is arranged to engage a fixed body-mounted stop 28 when the plug has been rotated to catch the tooth 13 behind the pawl 18; in this manner, the valve plug 8 is rotatable solely between the limiting positions imposed by utilizing the stops 27 and 28 to limit the rotary movements of the plug, which arrangement is understood to represent other devices which are usable for the same purpose.

It will now be noted that the pawl-controlling solenoids 21 and 22 are arranged to alternatively derive electric energy from a suitable source, as the secondary of a transformer 29, when a double-pole power supply switch 29' and individually operative switching devices of the timer 4 which are included in parallel branch circuits for the different solenoids, are closed. As is shown in FIGURE 3, the timer 4 provides a switch arm 30 mounted on a spindle 31 which is arranged for rotation at a uniform and relatively slow rate by a suitable means (not shown) for effecting a timed closing of the circuit of the solenoid 21 when a terminal contact portion 30' of the arm 30, which is included in said circuit, engages a fixed contact 32 in the branch circuit of the solenoid 22. An arcuate conductor 33 of the timer 4 is provided in the line of movement of the contact 30' of the switch arm 30 for its engagement by said contact, and the fixed switch contact 32 is disposed in the gap between the ends of the conductor 33, whereby the circuit-closing engagement of the arm 30 with the conductor 33 will close the circuit of the solenoid 21 for inoperatively disposing the pawl 17 with respect to the ratchet teeth of the member 12 only when the hand is out of engagement with the contact 32 and engages the conductor 33.

The timer 4 is mounted on and behind a conveniently located and mounted instrument panel 34 and has an indicator hand 35 extending from the spindle 31 of its switch arm 30 opposite the panel front. The point of the index hand 35 is arranged for movement along a numbered scale 36 provided on the panel front and calibrated for different time periods from a zero point corresponding to the contact 32, and the hand 35 is manually turnable to a selected point of said scale by the use of a turn-knob 37 fixed to the spindle 31 outwardly of the hand 35 for predetermining the time required for a closing of the switch 30-32 to effect the release of the teeth 13. As particularly illustrated, the operating handle for the switch 29' and the setting handle 8" of the valve 3 are also provided at the front of the panel 34 which mounts the switch 29' and the valve at its back.

Understanding that a tooth-releasing displacement of the pawl 18 effected by a closing of the circuit of the solenoid 22 is required only for a period long enough to release the tooth 13 to thereafter permit the closing of the valve by the action of the spring 11, the means rotating the spindle 31 carrying the switch arm 30 and index hand 35 is preferably arranged to carry the arm 30 beyond the contact 32 without engaging the arcuate contact 33 before the turning of the arm ceases, whereby the solenoid 22 is energized for a minimum time which is just sufficient for insuring a freeing of the valve plug for effecting a closing of the valve. Since the solenoid 21 is energized only while the arm 30 engages the arcuate contact 33, it will be understood that neither of the solenoids 21 and 22 is energized while the pres-

ent oxygen-dispensing apparatus is not operating; this feature comprises an important safety feature of the apparatus. While no structure is shown for the purpose, the means for operating the spindle 31 in the described manner may comprise a flat spiral spring which may be wound up by turning the knob 37 (and index hand 35) in a clockwise direction, and then utilizing the unwinding of the released spring to function through a usual escape-movement (not shown) to rotate the spindle in a counter-clockwise direction at a relatively slow rate until the terminal contact 30' of the controlled switch arm 30 engages the contact 32 and moves slightly therebeyond to a position in the gap between the contacts 32 and 33.

The oxygen-providing tube 2 from the flask 1 to the panel-mounted valve 35 is of a suitable structure and length for its installation between the tank and valve. Also, the oxygen-delivering tube 5 extending from the valve 3 is preferably of a flexible structure and may be slidably engaged through the panel 34 at a tubular panel-mounted guide member 38 to facilitate the disposal and use of the mixing-and-delivery head 6 at a desired point which is fixed or moving with reference to the panel. In practice, at least the tube 5 of the oxygen-delivery line 2-5 will have a suitable pliable form-retaining structure for its ready and changeable bending to desired shape at appropriate points therealong for facilitating a secured positioning and support of the head 6 at or outwardly of the member 38 on the panel.

Understanding that the present apparatus may provide oxygen-reinforced air at and for an individual, it will be obvious that the discharge outlet from a present head 6 may have or assume the form of a face mask or a mouthpiece for a direct delivery of reinforced air therefrom to a person who may have the mixing head mounted on the clothing or body by a suitable attaching means (not shown), such as a hook or clip or the like. On the other hand, the present head 6 might be disposed to deliver the reinforced air in a larger or smaller closed space such as a therapy tent or a room. Also, a present head 6 may be carried about by a person moving about by mounting the head on the person's clothing or person by a suitable attaching means (not shown) for the purpose.

As disclosed in FIGURE 5, the mixing-and-delivery head 6 essentially comprises a multi-jet nozzle 41 threadedly and terminally carried by a tubular rigid member 42 which is suitably fixed to the discharge end of the flexible tube 5 as a terminal continuation thereof, with said nozzle arranged to discharge a circular line of jets of the undiluted oxygen forwardly into a mixing passage 43 provided in a laterally closed tubular bell-shaped member 44 into which air from the space at the immediate rear of the head is drawn by the jet action at such a rate that the oxygen delivered within the head is suitably mixed with air therein to provide the desired oxygen-reinforced air. The present member 44 is threadedly mounted at its rear end on the periphery of a flat annular disc member 45 which is rotatively adjustable with the member 44 on and about the member 42, and is provided with a plurality of air inlet openings 46 transversely therethrough, and the member 44 extends appreciably beyond the nozzle 41 for the extension of the passage 43 well beyond the nozzle.

It will now be particularly noted that the member 45 is arranged for a jet-induced flow of atmospheric air into its rear end through the air inlet openings 46 at a regulatable rate by reason of its rotary adjustability with respect to corresponding transverse air-inlet openings 47 provided in a flange 48 extending fixedly from the nozzle-carrying member 42 outwardly of and closely adjacent the portion of the member 44 providing the openings 46 thereof. As particularly illustrated in FIGURE 5, the flange 48 extends integrally from a collar 49 which is threadedly mounted on the exterior of the member 42, it being understood, however, that the flange might

be provided as an integral intermediate portion of the member 42. Understanding that air-intake ports of variable effective cross-sectional area may be provided by relatively rotating the ported members 45 and 48, the present arrangement essentially provides for a retainedly swiveled engagement of the member 45 with the member 42 while the member 45 is held against the opposed face of the member 48.

As particularly indicated, the inner end of the threadedly-mounted nozzle 41 is arranged to axially engage a thrust ring 51 between it and the opposed inner side face portion of the member 45, whereby the head 6 is swiveled upon the member 42; the ring 51 may comprise an axially operative transversely-rippled spring for frictionally retaining the head 6 in rotatively adjusted relation to the flange 48, or a flat ring 51 may be clamped against the inner edge portion of the flange 48 by the screwing-up of the nozzle on the member 42 to positively fix the members 42 and 48 in rotatively adjusted relation. Essentially, the member 42 and flange 48 are cooperative as an adjustable air inlet valve in accordance with the adjusted degree of overlap of their respective openings 46 and 47, which openings are of like number and are uniformly spaced in coaxial circular lines of like circumference.

As particularly shown, the forward end of the member 44 externally and threadedly mounts a ring member 53 defining a circular discharge opening 54 at and across which a mesh screen 55 is mounted as a gas-mixing means thereat. For further assuring a complete mixing of the induced air with oxygen, and/or another gas, discharging from the nozzle 41, the bore of the tubular member 44 preferably has inwardly-directed flow control vanes 56 so formed and related that they define between them forward portions of the passage 43 having a similar spiral relation to the axis of the head, with the radial inner vane ends generally opposite and spaced slightly forwardly of the discharge end of the nozzle 41, whereby the oxygen stream through the member 44 is arranged to induce a forward spiraling air-flow through the passage of the member 44 in accordance with the effective air intake port provided through the air valve means at the rear inlet openings 46 and 47 and so assure a uniform reinforcement of the inspirated air with the oxygen delivered from the nozzle 41 by reason of the turbulence produced by the flow of the air and oxygen along the vanes to and through the screen 55.

Having the adjusted dispensing head 6 of the present apparatus disposed to deliver enriched air where desired, a person setting this apparatus would first close the switch 29', then turn the knob 37 for setting the timer index hand 35 at the desired timing position for oxygen delivery, and finally turn the freed valve plug 8 by means of its setting handle 8" to open-valve position and its retention therein by the engagement of the tooth 15 behind the pawl 18. Upon the automatic timed release of the time-setting knob 37, the switch arm 30 will move along the arcuate conductor 33 at the rate determined by the arm-operating mechanism until it moves from contact with the conductor to de-energize the solenoid 21 for restoring the pawl 17 to its operative position. The continued movement of the arm 30 to engage the contact 32 will energize the solenoid 22 to inoperatively dispose the pawl 18 for freeing the valve plug 8 for its spring-actuated closing, while the hand 35 stops beyond the contact 32 and before it again engages the arcuate conductor 33. In this manner, an operative cycle of the present apparatus is started solely by the two manual operations of setting the timing index and opening the valve, and is terminated by the purely automatic closing of the valve after the desired air-enriching charge of oxygen has been delivered through the appropriately set mixing head 6.

Referring generally to the specifically disclosed use of the present unitary apparatus for providing oxygen-reinforced air for breathing, it is particularly important to understand that the control features are designed to render the unit particularly safe for setting by the person who is to utilize the enriched air, both by reason of the preliminary valve and mixing-head adjustments which control the composition of the air provided for breathing, and the provision for automatically preventing an accidental or overlong supplying of the enriched air from the mixing and dispensing head 6. Although the present apparatus has been particularly designed for enriching atmospheric air with oxygen supplied from a container of compressed oxygen, it will be obvious that the enriching gas might include or wholly comprise therapeutic ingredients for providing a desirable air mixture for breathing.

From the foregoing description taken in connection with the accompanying drawings, the advantages of the present oxygen dispensing apparatus will be readily understood by those skilled in the art to which the invention appertains. While I have shown and described a structure and operative arrangement which I now consider to comprise a preferred embodiment of my invention, I desire to have it understood that the disclosure is primarily illustrative, and that such changes and developments may be made, when desired, as fall within the scope of the following claims.

I claim:

- 30 1. In a device for intermittently releasing charges of fluid from a source of fluid under pressure; a valve, means biasing said valve to closed position, manual operating means for moving said valve to open position, first biased latch means for normally preventing manual actuation of said valve from closed to open position, second biased latch means for locking the valve in open position, first unlocking means for said first latch means, second unlocking means for said second latch means, timer means of the type having actuator means manually settable from position where the timer means is inoperative to a desired operative position where the timer means will operate for a desired predetermined time, circuit means coacting with the timer means and the first and second unlocking means in such a manner that when the timer actuator means is moved from inoperative position to a desired operative position said first unlocking means is operated to thereby free the valve to be manually actuated from closed to open position and when the timer means has operated for said predetermined time said second unlocking means will be operated to unlatch said valve from open position so that said valve biasing means will reclose the valve.
- 35 2. A device according to claim 1 wherein said latching means comprise pivoted pawl means coacting with teeth connected to the valve.
- 40 3. A device according to claim 2 wherein said unlocking means comprise electromagnets which coact with armatures carried by said pawl means, said timer means comprises sliding contact switch means and said circuit settable from position where the timer means is inoperative to a desired operative position where the timer means will operate for a desired predetermined time, circuit means coacting with the timer means and the first and second unlocking means in such a manner that when the timer actuator means is moved from inoperative position to a desired operative position said first unlocking means is operated to thereby free the valve to be manually actuated from closed to open position and when the timer means has operated for said predetermined time said second unlocking means will be operated to unlatch said valve from open position so that said valve biasing means will reclose the valve.
- 45 4. A device according to claim 2 wherein said unlocking means comprise electromagnets which coact with armatures carried by said pawl means, said timer means comprises sliding contact switch means and said circuit settable from position where the timer means is inoperative to a desired operative position where the timer means will operate for a desired predetermined time, circuit means coacting with the timer means and the first and second unlocking means in such a manner that when the timer actuator means is moved from inoperative position to a desired operative position said first unlocking means is operated to thereby free the valve to be manually actuated from closed to open position and when the timer means has operated for said predetermined time said second unlocking means will be operated to unlatch said valve from open position so that said valve biasing means will reclose the valve.
- 50 5. A device according to claim 1 wherein said valve biasing means comprises a spring having a free end which is normally biased to close the valve and which is normally biased to open the valve when the timer means has operated for a predetermined time, the valve being normally closed by the spring and normally open by the timer means.
- 55 6. A device according to claim 1 wherein the timer means comprises a timer having a timer actuator means which is normally inoperative to move the timer index hand to a predetermined position, the timer index hand being normally settable to the predetermined position by the timer actuator means and normally resettable to a position other than the predetermined position by the timer means.
- 60 7. A device according to claim 1 wherein the timer means comprises a timer having a timer actuator means which is normally inoperative to move the timer index hand to a predetermined position, the timer index hand being normally settable to the predetermined position by the timer actuator means and normally resettable to a position other than the predetermined position by the timer means.
